Primary Examiner — Susan Bennett Hattan*Assistant Examiner* — Leanne Was-Englehart(74) *Attorney, Agent, or Firm* — Womble Carlyle Sandridge & Rice, LLP(57) **CLAIM**

The ornamental design for a threshold cap, as shown and described.

DESCRIPTION

FIG. 1 is an end view of our new design;

FIG. 2 is an end perspective of our new design;

FIG. 3 is an end view of our new design shown in a first position relative to environmental elements; and,

FIG. 4 is an end view of our new design shown in a second position relative to environmental elements.

The views not shown form no part of the claimed design. The dash-dot lines in FIGS. 1-4 represent unclaimed boundaries of the present design. The dash-dot-dot lines in FIGS. 1-4 represent environmental elements only and form no part of the claimed design.
